UNITED STATES PATENT OFFICE.

SETH WILLIAM BABBITT, OF MERIDEN, CONNECTICUT, ASSIGNOR TO THE
WILCOX SILVER PLATE COMPANY, OF SAME PLACE.

DESIGN FOR THE ORNAMENTATION OF SILVER OR OTHER TABLE-WARE.

SPECIFICATION forming part of Design No. 19,701, dated March 18, 1890.

Application filed December 24, 1889. Serial No. 334,895. Term of patent 3½ years.

To all whom it may concern:

Be it known that I, SETH WILLIAM BABBITT, a citizen of the United States, residing at Meriden, in the county of New Haven and State of Connecticut, have invented and produced a new and original Design for the Ornamentation of Silver or other Table-Ware; and I do hereby declare the following to be a full, clear, and exact description of said invention, reference being had to the accompanying photographs, and to the letters of reference marked thereon, which form a part of this specification.

In said photographs several different articles are shown, each having my design impressed thereon.

The leading feature of my design consists in an ornamentation for the surface of silver or other table-ware, said ornamentation comprising repeated flowers of similar appearance scattered rather closely over a roughened groundwork, each flower having a raised center and radiating petals.

A is the raised center, which is circular in its general contour, and a' a' are the groups of lines radiating therefrom, and each group is partially inclosed by a curved line. The meeting of the curved lines gives the appearance of a scallop-line B, surrounded or inclosing the groups of radiating lines, the whole design having the appearance of a flower, of which the raised surface A is the center and the spaces inside the curved lines are the petals. The surface inside the scallops is smooth, while the surface between the scallops of repeated flowers is rough or matted, as at C.

What I claim is—

The design for the ornamentation of silver or other table-ware, as shown and described. 40

In testimony whereof I affix my signature in presence of two subscribing witnesses.

S. WILLIAM BABBITT.
